MELVIN B. FEIFER, Primary Examiner

FIG. 1 is a perspective view of the guide for the club head of a golf putter showing my new design;

FIG. 2 is a front elevational view thereof;

FIG. 3 is a rear elevational view thereof;

FIG. 4 is a plan view thereof;

FIG. 5 is a bottom view thereof;

FIG. 6 is a left side elevational view thereof; and

FIG. 7 is a right side elevational view thereof.

I claim:

The ornamental design for a guide for the club head off a golf putter, substantially as shown.
